WATCH DIAL

Nicholas Pitrelli, Brooklyn, N. Y.

Application March 20, 1957, Serial No. 45,340

Term of patent 14 years

(Cl. D42—1)

The figure is a front elevational view of a watch dial showing my new design, the broken line representation of a watch case and hands being for illustrative purposes only.

The watch dial is of conventional thickness. The dominant features of my design reside in the portion shown in full lines.

I claim:

The ornamental design for a watch dial, as shown and described.
